Inventor:
Claydus Dornier
by Emil Haas
Attorney.

UNITED STATES PATENT OFFICE.

CLAUDIUS DORNIER, OF FRIEDRICHSHAFEN-ON-THE-BODENSEE, GERMANY, ASSIGNOR
TO FIRM ZEPPELINWERK LINDAU GESELLSCHAFT MIT BESCHRÄNKTER HAFTUNG,
OF LINDAU-REUTIN, GERMANY.

LANDING GEAR FOR FLYING MACHINES.

Original application filed June 15, 1921, Serial No. 477,843, and in Germany December 4, 1920. Divided
and this application filed May 22, 1924. Serial No. 715,261.

My invention refers to flying machines and more especially to a flying boat and its particular object is to provide a machine of this kind which, is adapted to start from and 5 land on water, snow, ice or solid ground.

To this end a starting wheel or pair of wheels is mounted in the bottom of the boat substantially in the middle axis of the boat's hull which is provided with lateral fins, and 10 at the outer ends of these fins supporting wheels, spikes or runners are mounted. If the flying boat is designed to be used mainly for landing on snow or ice, the starting and landing wheels mounted below the 15 boat's hull can be replaced by sledge runners.

In the drawings affixed to this specification and forming part thereof, two flying boats embodying my invention are illustrated by way of example. In the drawings—

Figs. 1 and 2 are a side and front elevation, respectively, of a flying boat provided with a pair of wheels on the hull and a 25 spike at the end of each fin, while

Figs. 3 and 4 are similar views of a flying boat in which the wheels are replaced by sledge runners.

Referring first to Figs. 1 and 2, 1 is the 30 boat's hull with a self supporting wing 2 placed across it, the motor 3 and traction propeller 4 being mounted forward of the wing. A pair of large starting wheels 10 is mounted in a cavity provided in the bottom of the hull 11; 5, 5 are fins or stump wings extending laterally of the bottom portion of the hull and 12 are spikes resiliently mounted at the ends of the fins.

By mounting the starting wheels in a cavity of the boat's hull all the difficulties encountered with the carriages usually employed in connection with flying boats in order to enable them to start from solid ground are avoided, the more so as these 45 wheels can be mounted in the hull in an easily detachable manner.

The spikes mounted at the ends of the fins and which might as well be replaced by dis-

engageably mounted lateral wheels, serve for supporting the craft against lateral tilting. Another spike 6 can be mounted below the rear portion of the hull and preferably at a step provided on the bottom of the hull.

In the flying boat illustrated in Figs. 3 and 4 and which closely resembles the craft shown in Figs. 1 and 2, the starting wheels are replaced by sledge runners 14 mounted on the bottom of the hull, these runners being spaced wider apart in order to more 60 safely support the hull in starting and landing. These runners project so far below the bottom of the hull that this latter, when gliding on snow or ice is protected against injury.

I wish it to be understood that I do not desire to be limited to the exact details of construction shown and described, for obvious modifications will occur to a person skilled in the art.

I claim:—

1. Flying boat comprising a boat's hull, a wing, fins extending laterally of the forward portion of said hull, starting means mounted below the bottom of said hull, without projecting laterally thereof and supporting means at the end of said fins.

2. Flying boat comprising a boat's hull, a wing, fins extending laterally of the forward portion of said hull, a starting wheel mounted below the bottom of said hull without projecting laterally thereof and supporting means at the end of said fins.

3. Flying boat comprising a boat's hull, a wing, fins extending laterally of the forward portion of said hull, a pair of starting wheels mounted below the bottom of said hull without projecting laterally thereof and supporting means at the end of said fins.

4. Flying boat comprising a boat's hull, a wing, fins extending laterally of the forward portion of said hull, a starting wheel mounted in a cavity extending substantially in the middle line of the hull's bottom and supporting means at the end of said fins.

5. Flying boat comprising a boat's hull, a

wing, fins extending laterally of the forward portion of said hull, starting means mounted below the bottom of said hull without projecting laterally thereof and a spike at 10
5 at the end of each fin.

6. Flying boat comprising a boat's hull, a wing, fins extending laterally of the forward

portion of said hull, a starting wheel mounted below the bottom of said hull without projecting laterally thereof and a spike at 10
the end of each fin.

In testimony whereof I affix my signature.

CLAUDIUS DORNIER.
